PUSH SLEDGE

Gustav Anderson, Sallebyn, Sundals Ryr,
SwedenApplication May 29, 1946, Serial No. 672,928
In Sweden February 2, 1945Section 1, Public Law 690, August 8, 1946
Patent expires February 2, 1965

4 Claims. (Cl. 280—23)

1

The invention relates to improvements in push-sledges, the runners of which are made of flat-strips of iron and placed on edge. These runners will easily slide on ice and hard snow, but will also readily grate underneath the snow when the snow is less hard, and they will thereby impede the desired easy sliding of the push-sledge. This inconvenience can be overcome by turning the fore part of the runners 90°, in order to make this part of the runners rest flat on the ground. Also the back part of the runners may be turned 90°, only leaving the middle part of the runners standing on edge.

One form of the invention is illustrated in the accompanying drawing showing a push-sledge, the runners of which are turned 90° on both the fore part 1 and the back part 2 in respect to the middle part 3. Thus the middle part 3 stands on edge as usual, while the other parts 1 and 2 rest flat on the ground.

By making one or more parts of the runners to rest flat on the ground, the runners will not so readily grate underneath the snow, but will on the contrary pack the snow and slide over it. At the same time, the runners maintain their elasticity in the middle, so that the push-sledge may be steered and braked even as well as those with the runners unturned.

By the improvement described, this push-sledge may stand a heavier load than ordinary ones.

I claim:

1. In a push sledge a runner of flat strip material, said flat strip being placed on an edge thereof, a portion of said strip being twisted at right angles to the remainder of said strip and a substantial area of said twisted portion being in the plane of the lower edge of said strip.

2

2. A runner for push sledges comprising a strip of resilient material having two relatively narrow sides and two relatively wide sides, said strip being twisted to bring a portion of one of said narrow sides and a complementary portion of one of said wide sides into alignment in the same plane to make surface contact.

3. A push sledge having a plurality of runners of resilient strip material, said runners each having two relatively narrow sides and two relatively wide sides, each said strip being twisted to bring a portion of one of said narrow sides and a complementary portion of one of said wide sides into alignment in the same plane to make surface contact.

4. A runner for push sledges comprising a strip of resilient material having two relatively narrow sides and two relatively wide sides, said strip being twisted at each end thereof to bring a central portion of one of said narrow sides and the complementary end portions of one of said wide sides into alignment in the same plane to make surface contact.

GUSTAV ANDERSON.
